UNITED STATES PATENT OFFICE.

GEORGE D. BELDIN, OF MARENGO, ILLINOIS.

COMBINED PITCHFORK AND SHOVEL.

SPECIFICATION forming part of Letters Patent No. 611,312, dated September 27, 1898.

Application filed March 5, 1898. Serial No. 672,797. (No model.)

To all whom it may concern:

Be it known that I, GEORGE D. BELDIN, a citizen of the United States, residing at Marengo, in the county of McHenry and State 5 of Illinois, have invented certain new and useful Improvements in a Combined Fork and Shovel; and I do hereby declare that the following is a full, clear, and exact description of the same, reference being had to the annexed 10 drawings, making a part of this specification, and to the letters of reference marked thereon.

The present invention has for its object to provide a simple and effective device that is capable of use either as a fork or a shovel, as 15 circumstances may require, which object is attained by the construction substantially as shown in the drawings and hereinafter described and claimed.

Figure 1 of the drawings is a perspective 20 view showing the shovel-blade in position for use, the fork being under the same and the tangs thereof shown in dotted lines. Fig. 2 is a longitudinal vertical section showing the shovel-blade thrown over in position to be out 25 of the way when the fork is to be used, the shovel-blade when in position shown in Fig. 1 being indicated by dotted lines.

In the accompanying drawings, A represents the fork, and B the shovel-blade, both 30 of which may be of any form or construction found best adapted to the purpose.

The blade B is hinged in any well-known manner to the heel or rear portion of the fork A to enable it to be thrown back out of the 35 way when the fork is to be brought into use, as shown in full lines of Fig. 2 of the drawings. The shovel-blade B has rigidly connected thereto a notched and guide locking-ring C, which extends between the tangs of 40 the fork and through a slot a in the hollow shank d of the fork. The notches b c in the ring C are to enable the spring-actuated latch D to engage therewith to hold the shovel-blade in the two positions, as indicated in dotted 45 and full lines of Fig. 2. The latch D is adapted to work in the hollow shank d of the fork and has a pin e extending through a slot f in the shank, by which means the latch may be operated by the fingers to release it from 50 the notch in the ring C. A coiled spring g

is located in the hollow shank d and bears against the rear end of the latch D to hold it in engagement with the notch in the ring C.

A suitable handle may be connected to the shank of the fork, as shown at E, and may be 55 of any length found best adapted to the uses to which the device may be applied.

Any suitable spring-actuated latch may be substituted for that shown, so long as it will effectively engage the notches in the guide 60 and locking-ring to hold the shovel-blade in the two positions herein described.

In Fig. 1 of the drawings the shovel-blade is shown in position for use, the spring-actuated latch engaging the notch b in the ring 65 C, which holds the blade perfectly rigid and secure. When it is desired to use the fork, the latch is released from the notch by pressing back on the pin e, which will allow the shovel-blade to be brought into position, as 70 indicated in full lines of Fig. 2 of the drawings, the latch automatically engaging the notch c of the ring C, which holds the blade securely in position out of the way of the fork.

The latch, as will be understood, in both 75 instances automatically engages with the notches in the ring as the notches are brought in line with the latch, but in releasing the latch it has to be accomplished by pressing back on the pin e.

A very simple and effective device combining the two elements of a fork and shovel is provided that will possess the requisite strength and durability in garden or agricultural use and that can be manufactured and 85 placed upon the market at a comparatively small cost.

Having now fully described my invention, what I claim as new, and desire to secure by Letters Patent, is—

1. A fork and a shovel hinged thereto, a notched device rigidly connected to the shovel and adapted to move therewith, and a spring-actuated latch adapted to engage the notched device to hold the shovel-blade in the two positions, substantially as and for the purpose set forth.

2. A fork, a shovel-blade hinged thereto, a notched guide and locking-ring upon the blade and movable therewith, and a spring-

actuated latch adapted to engage the notches in the ring, substantially as and for the purpose described.

3. A fork and a shovel-blade hinged thereto, 5 a notched guide and locking-ring rigidly secured to the blade and movable therewith, said ring extending through a slot in the shank of the fork, and a latch working in the hollow shank and adapted to engage the notches in

the ring, a pin extending from the latch through a slot in the shank, and a spring bearing upon the rear end of the latch to hold it in engagement with the notch in the ring, substantially as and for the purpose specified.

GEORGE D. BELDIN.
